DOOR-OPERATING MECHANISM FOR HOPPER CARS

Application filed April 29, 1929. Serial No. 358,904.

This invention relates to door operating and securing mechanism for hopper cars, and concerns itself with means that will facilitate the opening and closing movements of the door on hopper cars and that will securely hold the doors in closed position.

The invention comprises the novel structure and combination of parts hereinafter described and more particularly pointed out and defined in the appended claims.

In the accompanying drawings which illustrate a preferred form of this invention and in which similar reference numerals refer to similar features in the different views.

On the drawings:

Figure 1 is a fragmentary side elevational view of a hopper car illustrating the application of this invention.

Figure 2 is a fragmentary top plan view 20 of the hopper car.

Figure 3 is a sectional view taken upon the line III—III of Figure 1.

Figure 4 is an enlarged sectional view taken upon the line IV—IV of Figure 2.

As shown on the drawings:

In the drawings there is shown a portion of a railway car having a hopper, which consists of a stationary side 1, ends 2, and a door 3, which is hinged to the car upon the side 20 of the hopper opposite the stationary side.

The invention in its broadest aspect consists of a member which is pivoted to the door 3, and a member pivoted to the stationary side 1 with means for pivotally connecting 30 said members. The arrangement is preferably such that the tension of the first member, when the car is in closed position, will tend to swing the second member in an upward direction. In other words, when the car is in closed position, the two members are off dead center with the result that the tension in the first member will tend to cause the same to swing in the opposite direction from that which is required to open the door.

The door 1 is hinged at its upper end by means of hinges 4, so that it may swing outwardly at its lower end as shown in dotted lines in Figure 4.

In the illustrated form of the invention, 50 the aforementioned members are in the form

of yokes 5 and 6. The yoke 5 is pivoted to the door by suitable means. In the present instance, a transverse Z bar is attached to the door 3 and a metal band or strip 8 is attached above each angle 7 and extends over the yoke. 55 The yoke 6 is pivoted to the side 1 of the hopper by side bearing brackets 9, which are secured to the side of the hopper.

It will be noted that the arms of the two yokes are sufficiently spaced apart so that 60 the same will pass along the ends of the hopper as shown in Figure 3. Means are provided for pivotally connecting the ends of the two yokes. In the present instance, this means is shown as consisting of a rod 10 which passes through suitable apertures in 65 the two ends of the yokes. A latch 11 which is in the form of a hook is pivoted to the stationary wall 1 of the hopper and is adapted for engaging over the rod 10 for maintaining 70 the parts in the position shown in Figure 4.

With reference to Figure 4, it will be noted that the pull or tension of the yoke 5 is in a direction above the pivoted part of the yoke 6 with the result that there is a tendency to impart an upward turning movement 75 to the yoke 6. This tendency serves to maintain the yoke 6 against swinging downwardly and releasing the door. When the door 3 is in closed position, it will be noted that the yokes are off dead center.

The operation of the foregoing described structure is as follows:

Assume that the door 3 is in closed position, and the yokes are in operative position, as shown in full lines in Figure 4. To open the door 3, the operator will swing latch 11 out of engagement with the rod 10. After this has been done, the operator may use a crow bar C (Fig. 4) to force the rod 10 downwards and swing the yoke 6 downwardly. This movement will carry the yoke 5 therewith and when the yoke 6 has been swung into a position as shown in dotted lines in Figure 4, the hopper door 3, will be opened. In closing the door 3, the operator will simply push the door shut or until the latch 11 can be engaged over the rod 10. As the pull of the main yoke 5 tends to swing the yoke 6 upwardly it will be appreciated that there is

very little, if any, liability for the yokes to come unlatched and allow the door to accidentally open.

From the foregoing, it will be apparent that a very simple and effective mechanism has been provided for operating hopper doors and maintain the same in closed position. It will be further appreciated that the mechanism may be readily applied to existing hopper cars as well as upon new ones.

We claim as our invention:

1. In a car having a hopper, a door hinged to one side of said hopper, a yoke pivoted to said door and having its arm extend along the outside of said hopper toward the other side, a second yoke pivoted to the other side of said hopper, a rod connecting the end of the two yokes, and a latch hook pivoted to the stationary side of said hopper for engaging said rod, said second yoke being off center with respect to the first yoke when said door is in closed position.
2. In a car having a hopper, a door pivoted to one side of the hopper, the other side of said hopper being stationary, a yoke pivoted to said door, a yoke pivoted to the stationary side of said hopper, means for pivotally connecting said yokes and means for securing said yokes upon the stationary side of said hopper.
3. In a car having a hopper, a door hinged to one side of said hopper, a yoke pivoted to said door, said yoke having arms extending toward the other side of said hopper, and means for releasably securing said yoke to the other side of said hopper.
4. In a car having a hopper, a door hinged to one side of said hopper, a yoke pivoted to said door, an auxiliary yoke pivoted to the opposite side of said hopper, means for connecting the ends of said yokes for simultaneously swinging movement, and means for securing said yokes in door closing position, the arrangement being such that the first yoke will exercise an upward swinging movement with respect to the second yoke when the door is in closed position.
5. In a car having a hopper, a door hinged to one side of said hopper, the other side of said hopper being closed, a member pivoted to said door, a second member pivoted to the stationary side of said hopper and intermediate the top and bottom thereof, a connection between said members and a latch hook pivoted to the stationary side of the hopper and engaging said connection and maintaining said members against downward swinging movement.

In testimony whereof, we have hereunto subscribed our names at Chicago, Cook County, Illinois.

AXEL WASBERG.
KENNETH J. TOBIN.
